METHOD OF MAKING SHEET MATERIAL

Henry Himmell, New York, N. Y.

Application August 23, 1943, Serial No. 499,715

2 Claims. (Cl. 28—74)

My invention relates to a new and improved fabric material and a new and improved method of making the same.

One of the objects of my invention is to provide a fabric material which is cheap and thin and porous, so that such material can be used for making tea-bags, and for many other purposes. If desired, the improved material can be reinforced and made waterproof at separated spots thereof, by means of waterproofing and reinforcing spots of resin. If desired, the improved material can be made wholly waterproof by applying a suitable waterproofing resin or the like. If desired the material may be made grease-proof or alcohol-proof with a suitable resin or sizing.

In addition to other uses, the improved material can be used for making containers and wrappings of all kinds and for all purposes, as a substitute for cheesecloth, etc.

Other objects of my invention will be stated in the annexed description and drawing which illustrates a preferred embodiment thereof.

Fig. 1 is a perspective view of a sheet of material of a well-known type, said sheet of material having been partially separated into two layers;

Fig. 2 is a sectional view on the line 2—2 of Fig. 1;

Fig. 3 illustrates a modification of the interior surface of one of said layers according to my invention; and

Fig. 4 is a sectional view on the line 4—4 of Fig. 3.

It has been well known for many years to use the Garnett machine in order to make a sheet of fabric material. The primary use of the Garnett machine is to comb out foreign substances from fibrous material, or to reduce waste to fiber form.

When a variation of this well-known machine is rapidly operated on cotton fibers, such machine causes the cotton fibers to interlace, in order to form a loose felt.

In the operation of this machine, after the loose felt has been formed, such loose felt is compressed between rolls and it is then sprayed with sizing material upon each exposed face thereof. The thickness of such well-known material is about .010 inch and over.

Fig. 1 illustrates how a sheet A of such material has been split into two layers of equal width. The outer faces 2 and 3 of said original sheet of material A are smooth, because they have been provided with sizing. The inner faces

of said two layers are rough or fibrous, because in making such well-known material, the sizing does not penetrate very deeply into the interior of the sheet A.

According to my invention, the sheet of material A is split or separated along its median plane 4, in order to provide two separate sheets of material, each of which is half the thickness of the original well-known sheet A. Said original sheet of material A can be split or separated into more than two layers.

After the sheet of material has thus been separated, the internal faces 2a and 3a of the respective layers are treated with sizing, so that said faces 2a and 3a are smooth and compact, like the original outer faces 2 and 3 of the original sheet A.

The finished sheet B which is shown in Fig. 4, is extremely thin and porous. It has smooth outer faces 2 and 2a, so that the improved material can be used in place of woven material for making tea-bags and for other purposes in which the material must be permeable to water. The improved sheet B can be treated with reinforcing adhesive such as waterproof resins and the like, at separated spots thereof. Such waterproofing adhesive may be applied in order to waterproof the entire sheet B.

It is necessary to size each exposed face of the original sheet A, so that said sheet A will have the necessary strength in order to make it possible to split the same into two or more thinner pieces.

The sizing can be applied to the original outer faces 2 and 3 by means of a spraying operation.

The additional sizing can be sprayed upon the inner faces 2a and 3a, in a separate operation, after the original sheet A has been separated into two or more layers. If desired, the additional sizing can be sprayed upon the internal faces 2a and 3a during the operation of splitting the original sheet into two or more sheets.

After the original sheet A has been split, the final sheets can be compressed between rolls before spraying or otherwise applying the additional sizing to the newly exposed outer faces.

When the exposed faces 2 and 3 of the original sheet of material A are treated with adhesive, said adhesive is substantially confined adjacent said exposed faces 2 and 3, so that the intermediate portion of said original sheet A has the fibers connected only by their interlacing, and said interior portion of the original sheet A is either wholly or partially free from the sizing or other adhesive. It is thus possible easily

to split the original sheet A into two or more sub-sheets, such as the sheets B.

I have described a preferred embodiment of my invention, but it is clear that numerous changes and omissions and additions can be made without departing from its scope.

I claim:

1. A method of forming a sheet of material which consists in interlacing fibers to form a felted original sheet which has opposed exposed faces, connecting said interlaced fibers adjacent said exposed faces by means of adhesive to make said exposed faces smooth and compact, while leaving said interlaced fibers unconnected by said adhesive at the interior of the sheet, and splitting said original sheet at said interior, and connecting the interlaced fibers at the newly-

exposed faces of said sheet of material by means of adhesive to make said newly-exposed faces smooth and compact.

2. A method of forming a sheet of material which consists in interlacing fibers to form a felted original sheet which has opposed exposed faces, connecting said interlaced fibers adjacent said exposed faces by adhesive to make said exposed faces smooth and compact, while leaving said interlaced fibers unconnected by said adhesive at the interior of said sheet, splitting said original sheet at said interior to form two split sheets, compressing said split sheets, applying sizing to the unsized faces of said compressed split sheets to make said last-mentioned faces smooth and compact.

HENRY HIMMELL.
